AIR CONDITIONING SYSTEM

William A. Wulle, Chicago, Ill.

Application February 27, 1935, Serial No. 8,489

6 Claims. (CL 257—244)

This invention pertains to a system for air conditioning enclosures such as the rooms of dwellings, automobiles and the like.

One of the objects of this invention is to provide an air conditioning system which may be useful the year round so as to warm the air in the winter time and to cool it in the summer time while making provision under either condition for maintaining a proper percentage of 10 humidity in the air treated.

Another object is to provide a system wherein the conditioning apparatus may be constructed in individual units applicable to the separate rooms of enclosures and provided with a medium 15 for tempering the air from a central service plant.

Another object is to provide novel apparatus for tempering the air either for warming or cooling and which will provide for maintaining a 20 proper humidity.

Another object is to provide such improved apparatus which may be so installed as to promote a circulation of the conditioned air in the enclosure in a simple and efficient manner.

Another object is to provide such apparatus and system whereby the air of the enclosure may be re-circulated in a continuous manner while a desired percentage of fresh air may be added from without the enclosure.

Another object is to provide a simple system whereby changes from winter to summer operation and the reverse may be made in a simple manner without requiring the attention of skilled operators.

Further objects will appear from the following description taken in connection with the accompanying drawings, in which

Figure 1 is a vertical sectional view, somewhat diagrammatic in form, illustrating a portion of an enclosure equipped with apparatus embodying this invention;

Figure 2 is a horizontal section about on line 2—2 of Figure 1, somewhat enlarged in scale;

Figure 3 is a vertical sectional view of a portion of an automobile illustrating the application of this invention to such a vehicle;

Figure 4 is a detail section on line 4—4 of Figure 3, illustrating the arrangement of the cooling unit;

Figure 5 is a detail section on line 5—5 of Figure 4;

Figure 6 is a detail sectional view illustrating the means for automatically emptying the moisture pan during summer operation;

Figure 7 is a sectional view of a unit installed

in an automobile showing another embodiment of this invention; and

Figure 8 is a sectional detail of a combined float valve and control switch for the moisture pan.

Proper air conditioning of any enclosure wherein people are expected to spend their time requires, first, tempering of the air—that is, adjusting the same to a proper temperature—and, second, adjusting the humidity of the air.

The tempering of the air changes with the seasons, and in most climes requires heating during the winter time and cooling during the summer. Similarly, the requirements for maintaining a proper humidity are different at different seasons.

During the winter, it is usually necessary to add moisture or humidify the air, while during warm weather it is usually desirable to extract moisture or de-humidify the air. A third requisite for proper air conditioning is to maintain a certain movement of the air within the enclosure, not only to cause a circulation which will carry the air through a conditioning cycle, but also because a certain degree of movement of the air adds to the comfort of the occupants of the enclosure.

In accordance with this invention, an apparatus is provided which may be adapted with very slight changes to function either as a heater or as a cooler of air. This apparatus is also adapted to induce movement of the air so as to establish a desired circulation. In accordance with the system of this invention, the air conditioning unit is provided in such a form as to be mountable on or near the ceiling of the enclosure and is so arranged as to promote a circulation from the unit outwardly along the ceiling so that the air travels toward the walls of the enclosure and then downwardly along or near the walls. A return circulation is induced upwardly toward the unit and the air is drawn into the unit at the middle thereof and again induced to circulate outwardly therefrom.

Referring now to the drawings and particularly to Figures 1 and 2, 1 designates the walls and 2 the ceiling of an enclosure of any type. In the figure, an ordinary room is represented. The ceiling 2 is shown spaced from the floor 3 thereabove by the space formed by the joists 4 in the usual manner of building construction.

The space between any pair of joists, indicated at 5, may be utilized as an auxiliary air duct whereby fresh air from outside of the building may be brought to the air conditioning apparatus.

In the illustration of Figure 1, the duct 55

is shown extending from the exterior of the building through the floor 3 to the unit 1.

The unit 1 is shown in Figure 1 as being mounted on the ceiling 2, but it may be mounted on the floor 3 or on any other suitable support.

The unit 1 is shown in Figure 1 as being mounted on the ceiling 2, but it may be mounted on the floor 3 or on any other suitable support.

The unit 1 is shown in Figure 1 as being mounted on the ceiling 2, but it may be mounted on the floor 3 or on any other suitable support.

- 5 is carried through the wall 1 to the outside, being closed by a suitable screen 6 to prevent the entrance of undesirable matter. A damper 7, of any suitable construction, controlled by a suitable handle 8, may be provided to close the duct 5 when desired. A suitable air filter 81 may be placed in this duct so as to remove dust and the like from the air admitted. This may be made removable for cleaning or renewal.
- 10 The duct 5 may be lined with a separate tube of metal or other suitable material where the nature of the space between floors makes such a lining desirable. In structures where this space is limited or absent, as in some concrete floor constructions, such a separate tube may be placed in the concrete or along the ceiling or floor above to provide the duct 5.
- 15 The air conditioning unit as illustrated in Figures 1 and 2, comprises a suitable base 9 supported in any suitable manner on the ceiling 2. Supported by circumferentially spaced studs 10 on the base 9 is a casing 11 adapted to support and house the tempering core 12. Removably mounted below the casing 11 is a moisture pan 13.
- 20 Mounted within the casing 11 and within the core 12 is a pressure blower 14 driven by a suitable motor 15 supported on a bracket 16 on the base 9.
- 25 The structure of the conditioning core 12 is illustrated in detail in Figure 2. It comprises a series of coil pipe sections 17 sealed at their ends into vertically extending headers 18 and 19. The arrangement is such that a tempering medium, such as hot or cold water, may be supplied to one of the headers, such as 18, and after circulating through the coils to the header 19, be returned to the supply system from the latter header. The coils 17 are additionally supported at spaced intervals by vertical plates or fins 20 positioned radially about the coils 17 and adapted to provide heat transfer surfaces and air guides forming between them radial air passages so as to induce the air to move outwardly therethrough under the action of the blower 14. The assembly of coils 17 thus forms a cylindrical structure providing a core for the tempering unit such that the air may be forced to pass therethrough and in contact with the pipes 17 and the fins 20 so that the temperature of the air is modified by a transfer of heat between it and said pipes. This core is supported on the bottom of the casing 11, which is flanged upwardly at 21, to form an upstanding internal rim surrounding a central opening formed by a downwardly extending flange 22 below the rim 21. The rim 21 provides a barrier to retain moisture of condensation, which may collect in the casing 11 by deposit of moisture on the core 12. The casing 11 may be provided with a drip opening 23, whereby this moisture may be discharged into the pan 13.
- 30 The pan 13 is removably supported on the casing 11 as for instance by a plurality of bayonet connections, one of which is indicated at 24. This provides for easy removal of the pan 13 for emptying the same. The central portion of this pan has an upwardly extending flange 25 providing a central duct or flue extending upwardly through the middle of the pan. This flange 25 is spaced from the flange 22 of the casing 11 so as to establish communication between the interior of the pan 13 and the interior of the casing 11 and the core 12 for a purpose which will be set forth presently. It will be seen that the pan 13 is thus arranged to receive moisture of condensation which may form on the core 12 when acting as a

cooling unit. From time to time the pan 13 may be removed and emptied.

The central portion of the base 9 has a downwardly extending flange 26 which also forms a duct or flue permitting the entrance of air from above the unit to the interior of the blower 14. The bracket 16 is made of spider form having openings therethrough to permit the entrance of air at this point. An opening 27 may also be provided in the ceiling just above the unit so as to permit air carried in by the duct 5 to pass into the tempering unit from the top.

In order to provide extra blower capacity for air circulation, the blower 14 carries upon the upper ends of its blades a flanged ring 28, carrying on its circumference an additional series of fan blades 29 extending horizontally between the base 9 and the upper flange of the casing 11. It will be noted that the casing 11 is formed with a space 30 surrounding the tempering core and communicating with the space in which the fan blades 29 move. It will further be noted that by this arrangement the blower 14 provides a pressure blower adapted to force the air through the tempering core from within while the blower 29 provides a suction blower tending to exhaust the space 30 and thereby drawing the air through the core from the outside and blowing it out horizontally along the ceiling through the annular opening between the base 9 and the upper flange of the casing 11.

The tempering medium, which may be hot or cold water or any other suitable means, may be supplied to the header 18 by a supply pipe 31 and, after circulating through the coils 17, may be returned from the header 19 by a return pipe 32. These pipes may be arranged to enter the device from the top and be run through the duct 5 or otherwise to any suitable point for connection to a heating or cooling system whereby the tempering medium may be properly conditioned. In Figure 1, the pipes 31 and 32 are carried through suitable valves 33 and 34 to a cold water tank 35. This tank may be cooled by any suitable means involving either the use of ice or similar refrigerating medium, or mechanical refrigeration. The latter is illustrated in Figure 1 and comprises the usual compressor 36, condenser 37 and receiver 38. From the latter a liquid line 39 runs through an expansion valve 40 to an evaporating coil 41 within the tank 35. The vapor from the coil 41 is returned by a suction line 42 to the compressor 36. This cooling system may be arranged to operate automatically in the usual manner so as to maintain a desired temperature in the water in the tank 35. A motor-driven pump 43 may be provided to pump the cooled water from the tank 35 up through the pipe 31 to the unit on the ceiling, the water then returning by the pipe 32 to the tank. While only one ceiling unit is illustrated in Figure 1, it will be understood, of course, that a plurality of such units may be installed in different rooms and that the pipes 31 and 32 may be suitably arranged to supply the tempering medium to all of such units.

In order to provide for heating the tempering core 12 in the winter time, the pipes 31 and 32 may have connected thereto branches 44 and 45 controlled by valves 46 and 47 and leading to a suitable water heater or other device for properly conditioning the tempering medium for winter service. With this arrangement, it is only necessary at the change of the seasons, say from summer to winter, to close the valves 33 and 34 and to open the valves 46 and 47 whereby

the air conditioning system may be converted from a cooling system to a heating system. The pump 43 may have its motor connected by a suitable circuit 48 with a controlling thermostat 49 adapted to regulate the operation of the pump in accordance with the temperature of the room. In the arrangement shown, a double throw switch S is provided whereby the thermostat 49 may be changed at the change of the seasons from the pump 43 to a suitable heating unit, such as an oil burner, not shown in the drawing. The thermostat 49 may be arranged with a double set of contacts, one closing the control circuit upon rise of temperature to a certain maximum (for summer service) and the other upon drop of temperature to a certain minimum (for winter service).

It is believed that the operation of this system will be clear from the foregoing description. The tempering medium, prepared by the refrigerating plant or a heating plant, is supplied by the pipes 31 and 32 to the tempering core 12, which serves as a heating or cooling core, as the case may be. Air is drawn into the unit, mostly through the lower opening to the interior of the blower 14, whereby it is forced through the radial passages between the plates 20 and so as to come into intimate contact with the coils 17 and plates 20 whereby its temperature is modified in accordance with requirements. Passing into the space 30, the air comes under the influence of the exhaust blower 29, which projects it outwardly from the unit along the ceiling and toward the side walls of the enclosure. Thus a natural circulation is promoted, extending horizontally near the ceiling and downwardly near the walls, where a down-current is established. The old air is then drawn upwardly through the unit and recirculated. During this operation a certain percentage of new air from outside the building may be drawn in through the duct 5, the percentage being controlled by the position of the damper 7. In place of the damper 7, a damper may be placed on the unit, as for instance, on the bracket 16.

In order to control the humidity of the air, the core 12, when acting as a cooling core, functions to de-humidify the air by the deposit of moisture on the cool surface of the core. This moisture collects in the casing 11 and passes by the opening 23 into the pan 13, which may be removed from time to time and emptied. When the unit is used for heating, moisture must be added to the air being treated. For this purpose the pan 13 also serves as a humidifying device. A coil of pipe 50, connected at 51 and 52 to the headers 19 and 18, respectively, is adapted to receive water from those headers. A drip valve 53 is provided in the coil 50, whereby water from said coil may be permitted to enter the pan 13. This valve is controlled by a float 54 so as to fix the maximum level of the liquid maintained in the pan 13. As the water received by the coil 50 from the headers 18 and 19 is hot, it will serve to heat the water collected in the pan 13 and thereby promote evaporation. The water vapor so formed will be induced to pass upwardly through the space between the flanges 22 and 25 to the interior of the blower 14 to be mingled with the air entering from below the unit and to be passed through the unit therewith. By this arrangement a proper quantity of moisture may be continually added to the air being circulated. The preparation of moisture vapor is positive, as the water provided for that purpose is heated

so that rapid evaporation is induced so the proper quantity of moisture is provided.

In providing for the proper humidity-conditioning of the air, the moisture pan 13 serves both for the purpose of adding moisture to the air during winter operation and for collecting moisture condensed in de-humidifying the air during summer operation. In accordance with this invention, therefore, means are provided for properly controlling the moisture in the pan 13 during both summer and winter operation.

In the arrangement shown in Figure 6, a pipe 82 leads from the bottom of the pan 13 by any suitable path to a pump 83, motor-driven or otherwise, which is preferably located at a lower level than the pan 13. The pump 83 is thus adapted, when in operation, to draw the water from the pan 13. As the pump is located below the level of the pan, it will be evident that when the pump has been operated for a short time, sufficient to start the downward flow of water in the pipe 82, the flow will continue by siphonic action. The pump should, of course, be so arranged as to permit the flow of water therethrough when the pump is not in operation. In order to make the operation automatic, the motor which drives the pump 83 may be controlled by a solenoid switch 84 operated by a control circuit 85 and controlled by a suitable float switch 86 in the pan 13. The circuit 85 may be a separate control circuit, such as a battery circuit, or it may be connected to the power circuit which supplies the pump 83. It will be seen that this arrangement provides for automatically starting the pump as soon as the water level in the pan 13 rises to a predetermined point, such as to close the float switch 86. A control switch 87 may be arranged to open the circuit 85 so that this action may be interrupted during winter operation. In such installations where it is desired to spare the expense of the motor pump equipment, the switch 86 may be arranged to control an alarm circuit whereby an audible or visual signal is displayed when the water level in the pan 13 reaches a pre-determined level. It may also be arranged so that instead of or in addition to the operation of an alarm, the circuit 85 operates to shut down the pump 83 so as to discontinue the circulation of the tempering medium and thus limit the deposit of moisture which may collect in the pan.

In some installations, it may be desirable to provide for the automatic change from winter to summer operation, and vice versa, in the handling of the water in the pan 13. For this purpose a special control switch may be provided, as illustrated in Figure 8. This is a flat switch which may be inserted in the coil 50 in place of the switch 53. It comprises a conduit section 88, which is included as a part of the coil 50. This section is provided with a drip nozzle 89 and associated with said nozzle is a shut-off cock, shown in section at 90. This may be a simple shut-off valve of the type used, for instance, in the drain cocks for automobile radiators. Within the conduit 88 and at the inner terminus of the drip passage, a valve seat 91 is formed adapted to cooperate with a vertically moving valve 92 controlled by the float 54. Said float is supported on a lever 93 pivoted at 94 on a suitable bracket on the conduit 88 and carrying at its other end the stem of the valve 92. Mounted on the conduit 88 is an insulating casing 95 within which is mounted a spring contact arm 96 adapted to engage an intermediate stationary contact 97. The arm 96,

by its own resiliency, tends to disengage the contact 87 so that an open circuit is established therebetween. A short plunger 88 rests on the arm 86 and is positioned for engagement by an arm 89 extending upwardly from the lever 83 in such a position that when the float 54 rises the arm 89 engages and forces downwardly the plunger 88 so as to move the arm 86 into contacting engagement with the stationary contact 87. A second contact arm 100 is also mounted in the casing 85 and arranged to engage the stationary contact 87. The arm 100 may be of bi-metallic construction so as to change its shape with change of temperature. The structure is such that at a low temperature the arm 100 engages the contact 87 so as to close an electric circuit between the two. The casing 85 is secured to the conduit 88 and is open thereto so that the temperature of the conduit may affect the arm 100. The construction is such that when hot water is circulating in the coil 58 and the conduit 88 is at a high temperature in consequence thereof, the heat radiated from the conduit will heat the arm 100, which, by the relative expansion of its different metals, moves to open the circuit between it and the contact 87. Connections from the arms 86 and 100 are brought out to binding screws 101 and 102, respectively, whereby this switch may be connected into the circuit 85 as described for the switch 86.

It will be noted that the operation of this switch is such that during the summer time when the air conditioning unit is operating with cold water flowing through the core 12, the low temperature causes the arm 100 to engage the contact 87. During such operation, the cock 80 is closed so as to prevent escape of water from the coil 58 into the pan 13. During operation under these conditions moisture collecting by condensation on the core 12 accumulates in the pan 13 and, when the level thereof rises to a proper point, the float 54 swings the arm 86 into engagement with the plunger 88, which in turn forces the arm 86 into engagement with the contact 87, thereby closing the circuit 85. This starts the pump 83, which draws off the water from the pan 13, and starts syphonic action through the pipe 82. Upon the reduction of the level of water in the pan 13, the float 54 drops and the arm 86 releases the contact arm 86 so that the control circuit is open. The pump 83 thereupon stops but the siphonic action continues until the pan 13 is drained. This action is entirely automatic so that the water of condensation need not require attention from one end of the season to the other.

When the change is made to winter operation, this switch automatically accommodates the circuit connections to such operation. The cock 80, having been opened, the heating system is set in operation and hot water is circulated in the coil 58 and is delivered to the pan 13. The heat of the conduit 88 causes the arm 100 to move away from the contact 87 and the control circuit of the pump 83 is opened and therefore the pump is rendered inoperative through the winter season. During the winter season, the float 54 operates to control the valve 82, which in turn regulates the level of the liquid in the pan 13.

In the embodiment illustrated in Figures 3 and 4, the system is applied to an automobile. In Figure 3, 55 represents the rear wall and 56 the roof of the car, while 57 represents the rear seat. The air conditioning unit is shown as mounted on the roof of the car near the middle of the interior enclosure. The circulation of air promoted thereby

is indicated by arrows as passing outwardly along the roof and downwardly at the sides, front and back while the air is drawn upwardly at the middle of the car so as to be re-circulated through the unit.

Figure 4 illustrates a cooling plant for cooling the tempering medium, which in this case again is taken as water. A suitable box or casing 58 may be mounted at the rear of the car or in any other suitable position. It has mounted therein a refrigerant container 59, which may contain ice or other suitable medium for cooling. Below the bottom of the tank 59, a sump 60 is provided, separated from the body of the tank by a suitable screen or grating 61. The water formed by melting of the ice, or provided in any other manner, collects in the sump 60. This is connected by a suction pipe 62 with a motor-driven pump 63, whereby the water is circulated through a pipe 64 to the tempering core 12 at the top of the car. The water, after passing through the core 12, returns by a pipe 65 to a spray head 66 mounted in the tank 59. The returning water thus enters the tank 59 in a spray by which it is distributed over the ice contained in the tank to be cooled thereby, and then returns to the sump 60 to be re-circulated.

The pipes 64 and 65 are preferably in the form of rubber hose and are carried to the conditioning unit at the top of the car through a conduit 67, which may be arranged to pass upwardly within the rear wall and roof of the car, as illustrated in Figure 3. This conduit is dimensioned so as to be capable not only of accommodating the pipes 64 and 65, but also of providing additional space sufficient to permit the passage of an air supply along this duct to the unit at the top of the car. The duct 67 enters the box 58 near the bottom thereof and in a compartment 68 within which the tank 59 is mounted. This compartment is open to the outside atmosphere through a series of perforations 69. Accordingly, the outer air is admitted to this compartment and coming in contact with the tank 59 is somewhat cooled thereby. This air is drawn by the action of the blower 14 from the compartment 68 through the conduit 67 and is supplied to the unit through an opening 70 in the car roof. This air may also be provided by a simple opening passing directly through the car roof to the outer atmosphere. In such case, however, provision must be made for the exclusion of rain, snow and the like.

While connections for heating the car in the winter time are not shown in these figures, it will be understood that a suitable heating medium may be arranged to be supplied by the pipes 64 and 65 or by other similar pipes passing to any suitable type of heater with which the car may be supplied.

The action of the conditioning unit in this case is similar to that described for Figures 1 and 2.

In order to apply this invention to automobiles already in existence and which may not be equipped with a conduit 67, the arrangement of Figure 7 may be provided. In this case, the air-conditioning unit is mounted at the top of the interior of the car in the same manner as described for Figure 3. In place of the conduit 67, however, a conduit 103 passes from the middle of the lower portion of the unit downwardly through the floor 104 of the car and then rearwardly, as indicated at 105, to the casing 58. Its connection to the casing may be the same as described for Figure 3. The tubes 64 and 65 are 75

passed to the unit through the conduits 105 and 108. Also the supply of outside air passes through these conduits as described for the conduit 67. The collection of moisture, which in the embodiment of Figure 3 was retained in the pan 13, will now pass downwardly through the conduit 103 and be discharged at a drip nozzle 106.

In the embodiment of Figure 7, a so-called flat type of tempering core is illustrated. This is similar in construction to an ordinary automobile radiator, but its tubes are arranged horizontally instead of vertically. Headers 107 and 108, corresponding to the headers 18 and 19, are connected by a plurality of tubes 68, which may be equipped with transverse fins for conduction of heat in the usual manner. The tubes 64 and 65 are arranged to enter the headers 107 and 108. The tempering medium is thus circulated through the tubes 108 while the air passing into the casing 110, by means of a plurality of inlet openings 111, is passed upwardly through the tempering unit and then delivered outwardly along the top of the car by the fan 29, driven by the motor 15.

The embodiment of Figure 7 is not limited to the flat type of tempering core, but may be constructed in all respects similar to the arrangement of Figure 3 by simply leading the tempering medium thereto through the conduit 103 instead of the conduit 67 enclosed in the roof and walls of the car. It will be understood, furthermore, that the flat type of tempering core may be used in the embodiment of Figure 1 where conditions make such an arrangement necessary or desirable.

It will be seen that this invention provides a system of great simplicity for air conditioning any type of enclosure. The unit is compact and may be proportioned for high efficiency in the tempering and conditioning of the air. It is adaptable to any type of enclosure and particularly to such small enclosures as automobiles. In larger enclosures, a plurality of units may be installed with suitable spacing so that practically any type of enclosure may be provided for.

The unit provides for all the functions necessary for proper air conditioning. The air may be tempered by either heating or cooling and at the same time is properly humidified or de-humidified according to requirements. At the same time, the blower furnishes a forced circulation so that the proper amount of air movement may be maintained, and, of course, the continual circulation provides for continual re-conditioning of the air as circumstances require.

While this system has been described as a unitary whole, it will be understood that certain individual features or sub-combinations thereof may be useful by themselves without reference to other features, and that the employment of such individual features or sub-combinations in contemplated by this invention and within the scope of the appended claims. It will be further obvious that the various different features illustrated and described may be combined in any desired manner to provide different combinations

suitable for special circumstances, and that such variation in the combinations is also contemplated by this invention. It is further obvious that various changes may be made, within the scope of the appended claims, in the details of construction without departing from the spirit of this invention; it is to be understood, therefore, that this invention is not limited to the specific details shown and/or described.

Having described the invention, what is claimed is:

1. In an air-conditioning system for enclosures, an air-conditioning unit mountable at the ceiling of the enclosure, temperature-conditioning means within said unit, means for moving air through said unit and discharging it laterally along the ceiling, a water pan beneath said unit, means for automatically supplying water to said pan, and an air inlet to said unit passing through said pan.

2. In an air-conditioning system of the character described, an air-tempering unit arranged in circular form and having guiding means providing a radial air passage therethrough, a pressure blower adapted to force air from within said unit outwardly through said passage, and a suction blower moving radially beyond said passage adapted to withdraw air from the outer end of said passage.

3. In an air-conditioning system of the character described, an air-tempering unit arranged in circular form and having guiding means providing radial air passages therethrough, a pressure blower adapted to force air from within said unit outwardly through said passages, and a suction blower moving radially beyond said passage adapted to withdraw air from the space surrounding said unit.

4. In an air-conditioning system of the character described, an air-tempering unit arranged in circular form and having guiding means providing radial air passages therethrough, a pressure blower adapted to force air from within said unit outwardly through said passages, and a suction blower moving radially beyond said passage adapted to withdraw air from the space surrounding said unit and to project the same radially outwardly into the space to be conditioned.

5. In an air-conditioning system for automobiles, means for conditioning a tempering agent, an air-tempering unit mounted in the upper part of the interior of the car, and a conduit housed within the walls and roof of the car through which air and the conditioned tempering agent are conveyed to said unit.

6. In an air-conditioning system of the character described, an air-tempering unit arranged in circular form and having means providing radial air passages therethrough, a casing for said unit having a lower central inlet and a peripheral outlet above said unit, and a suction blower moving above and radially beyond said passages to draw air through said inlet and said passages and blow the same outwardly from said outlet.
